UNITED STATES PATENT OFFICE

138,662

DESIGN FOR A WRENCH

Otto Swanstrom, Duluth, Minn.

Application February 4, 1944, Serial No. 112,445

Term of patent 14 years

(Cl. D54—16)

To all whom it may concern:

Be it known that I, Otto Swanstrom, a citizen of the United States, residing at Duluth, in the county of St. Louis and State of Minnesota, have invented a new, original, and ornamental Design for a Wrench, of which the following is a specification, reference being had to the accompanying drawing, forming part thereof.

Fig. 1 is a side elevational view of a wrench showing my new design, and

Fig. 2 is a front elevational view of Fig. 1.

Fig. 3 is a sectional view taken on the 3—3 of Fig. 1. The characteristic features of my design reside in the wrench jaws shown in full lines, and particularly in the forward portions thereof.

I claim:

The ornamental design for a wrench, as shown and described.

OTTO SWANSTROM.
